UNITED STATES PATENT OFFICE

BIRGER UNDERDAHL, OF PORTLAND, OREGON

DENTURE PRESS

Application filed August 17, 1928. Serial No. 300,325.

The general object of my said invention is the provision of a denture press, simple and sturdy in construction, and susceptible of ready and efficient manipulation to assure the production of accurate results.

To the attainment of the foregoing, the invention consists in the improvement as hereinafter described and definitely claimed.

In the accompanying drawings, forming a part of this specification:

Figure 1 is an elevation of the preferred embodiment of my invention.

Figure 2 is a view of the same, partly in diametrical section and partly in elevation, the flask frame being partly in elevation and the two flasks shown in combination with the frame as part of my invention being shown entirely in elevation.

Figure 3 is an enlarged detail elevation of the press base per se.

Figure 4 is an enlarged detail horizontal section taken in a plane below the head of the flask frame, looking upwardly and showing the pendant studs on the boiler cover for accurately positioning and centering the flask frame.

Figure 5 is an enlarged horizontal section taken through one of the flasks.

Figure 6 is a horizontal section taken through the complete press in a horizontal plane above one of the flasks and showing the positioning of the flask in the flask frame and the manner in which casual displacement of the flask from the frame is prevented, due to co-action between the flask and one of the said uprights of the flask frame.

Figure 7 is an enlarged fragmentary diametrical section of one of the flasks showing the manner in which the lugs of the flask sections are interlocked.

Similar numerals of reference designate corresponding parts in all of the views of the drawings. The boiler 1 of the press is preferably formed of aluminum appropriately embellished by nickel plating or otherwise, and it is open at its upper end and is provided with a bottom 2 below its lower end. The portion of the boiler 1 below the bottom 2, in the present embodiment of my invention, is provided with apertures 3, for the admission

of air to support combustion and for the emission of products of combustion. The said boiler 1 is provided, in its lower end with recesses 4 designed to receive upstanding projections 5 on the base 6, Figures 1, 2, and 3, whereby when the boiler 1 is rested with its lower end on a shelf 7 of the base 6, the boiler 1 and the base 6 will be interlocked and turning of the boiler 1 about its axis with respect to the base 6 will be prevented. Notwithstanding this, however, it will be manifest, that the boiler 1 may be expeditiously and easily lifted from the base 6 and may as readily be replaced on and interlocked with the base 6. Said base 6, in addition to a body 8, characterized and just described, includes legs 9 and is equipped with an appropriate gas burner 10.

Manifestly, within the purview of my invention, an electric heating element may be employed in lieu of the gas burner 10 as an appurtenance of the base 6 and when the electric heating member is employed, the apertures 3 in the lower end of the boiler 1 may be either employed or altogether omitted in the discretion of the manufacturer of the press. The cover for the boiler 1 is designated by 10 and it is preferably, although not necessarily, equipped with a safety valve 11, a thermometer 12 and a pet cock 13, all in communication with the interior of the boiler 1. The pet cock 13 is provided, by preference, in order that an operator by opening the pet cock 13 may be sure that the interior of the boiler 1 is practically free of steam, before the cover 10 is removed.

The said cover 10 is provided with a pendant flange 14 that is designed to fit snugly in the upper end of the boiler 1 and is also provided with a central aperture 15, Figure 2.

The flask frame of my improvement is designated by 16, and it is provided in its upper end portion or head 17 with a threaded aperture 18 to receive the pendant threaded portion of a stud 19, which is flanged at 20 to bear on the upper side of the cover 10 and is interiorly threaded at 21 and is exteriorly threaded at its upper end to receive an aper-

tured gland 22, in which is a packing annulus 23.

In order to center and properly position the flask frame 16, the cover 10 is provided with pendant projections 24, Figure 4, designed to cooperate with opposite edges of the head 17 in which edges are seats 25, whereby as will be readily apparent the flask frame 16 may be accurately centered and positioned for the reception of the pendant threaded portion of the nut 19. It will also be understood that the co-action between the flask frame 16 and the projections 24 will preclude turning of the flask frame 16 about its axis and in that way will prevent shifting in position of the flask frame when the parts are assembled and connected as shown in Figure 2.

Extending through and engaging the nut 19 is a screw stem 26, to the lower end of which is connected by a pawl and socket joint a follower plate 27, (Figure 2).

At its upper end, the stem or shaft 26 is provided with a handle 27, which may be of the form illustrated or any other form compatible with the purposes of my invention.

The cover 10 may be secured on the boiler body 1 in any appropriate manner. I prefer, however, to employ for the purpose the swingable bolt 28, pivotally connected at 29, to lugs on the boiler body 1 and adapted, when swung to the vertical positions shown in Figure 1 to enter bifurcations in projections 30 on the cover 10. The said bolts 28 are equipped with wing nuts 31, Figure 1, and when the bolts are positioned, as shown in Figure 1, the said wing nuts 31 are designed to be turned down tight on the cover 10, so as to bring about a tight or hermetic closure of the boiler.

In addition to the head 17, the flask frame 16 which is preferably formed in one piece of appropriate metal includes a bottom plate 32, spaced considerably below the head 17, and upright bars 33 and 34 interposed between and adjoining the head and bottom plate and spaced apart (Figure 2). The upright bar 33 is peculiar and advantageous in that it is provided at one of its vertical edges with an inwardly directed lip 35, Figures 4 and 6, for an important purpose presently pointed out.

In the illustrated embodiment of my invention, two flasks 36 are shown in superposed relation in the frame 16, though I would have it understood that any desired number of the flasks 36 may be so employed. In this connection, it will also be understood that the flask frame 16 may be made of any desired length as may also the boiler 1. The flasks 36 are identical in construction, and therefore a detailed description of the flasks shown in Figures 5, 6, and 7 will suffice to impart a definite understanding of both or all flasks 36. The flask specially alluded to includes a lower section 40 and an upper section 41, the

said sections being of such construction that viewed from above each flask has a concave side 41, and a convex side 42, Figures 5 and 6. The meeting edges of the sections 40 and 41 are provided with notches 43, which, when registered as shown in Figure 7, are calculated to afford vent apertures for the exudation of plaster of Paris or similar matter from the flask incident to a denture operation. It is important that the said vent apertures of the flask be so relatively arranged that when the flasks are superimposed in the frame 16, vent apertures such as described will rest at opposite sides of the lips 35 on the uprights 33 of the flask frame 16. See in this connection the dotted lines representing the said apertures in Figure 6 of the drawings.

The bottom section 40 of the special flask referred to, is shown in plan Figure 5, and from said figure it will be understood that there are many of the vent apertures such as described in the side of the flask. It will also be understood that the section 40 is provided exteriorly with lug seats 44, the interiors of which are of concaved form in horizontal section as designated at 45 in Figure 5. The upper section 41 of the flask referred to is preferably provided in its top with vent apertures 46, (Figures 6 and 7). It will be also noted that the said section 41 is provided at opposite points with exterior projections 47 and that said projections 47 carry pendant tongues 48, which are tapered toward their lower ends, as are also the seats 45, before referred to.

I would also have it understood that the faces of the tongues 48 are of convex form in horizontal section as designated by 49, in Figure 5.

By virtue of the peculiar form of the pendent tongues 48 and the lug seats 45, it will be understood that when the section 41 is spaced above the section 40 with the lower end portions of the tongues 48 in the upper ends of the seats 45, the section 41 may be rocked or manipulated with respect to the section 40. When, however, the section 41 is moved down tight on the section 40, the tongues 48 will be snugly disposed in the seat 45 after the manner of a wedge action, and in consequence the sections 40 and 41 will be joined in such manner that there is absolutely no liability of edgewise shifting movement of either of the sections 40 and 41 with respect to the other. The relative arrangement of the vent apertures formed by the notches 43 of the flask sections 40 and 41 is very advantageous because in the event of exudation of plaster of Paris or other material from the flask through said apertures, there is no liability of any of the plaster of Paris or other material getting on the lip 35 of the flask frame bar 33.

When the flasks 36 are positioned in superimposed relation in the frame 16, Figure 2,

and the stem or shaft 26 is turned about its axis to impose pressure through the follower plate 27 on the flask 36, the tendency is to move the flask in the direction indicated by the large arrow in Figure 6.

It will be appreciated, however, from Figure 6, that when the action indicated takes place, the convex sides of the flasks, cooperating with the lip 35 of the upright 33 and the concaved sides of the flasks cooperating with the frame bar 34 will absolutely prevent material shifting or movement of the flask in the frame 16, which is a highly important advantage. It will be noted, however, in this connection, that when the boiler is opened, and the frame and flasks are removed, from the boiler body 1, movement of the flask in the direction opposite to that indicated by the large arrow in Figure 6 will bring about removal of the flask from the frame 16, and then, as will be readily understood, the flask sections may be expeditiously and easily disconnected for access to the interiors of the flasks.

In practice, not only the boiler 1, but all of the other exposed parts of my novel press are preferably, although not necessarily nickel-plated or otherwise embellished in order to enhance the finished appearance of the press as a whole.

I have specifically described the preferred embodiment of my invention, in order to impart a full, clear and exact understanding of said embodiment and all of its details.

I do not desire, however, to be understood, as limiting myself to the structural details illustrated, my invention being defined by my appended claims, and within the scope of which modifications may be made without

departure from my invention.

I claim:

1. In a denture press, and in combination, a flask frame having spaced upright bars, one with an inwardly directed lip extending from one of its upright edges, and a flask for removable arrangement in said frame, the flask concaved at one side for opposition to and reception of one upright bar of the frame and convex at its opposite side for opposition to and cooperation with the lip on the other bar of the frame.

2. In a denture press, and in combination, a boiler open at its upper end, an apertured cover for the boiler, means for detachably securing the cover on the boiler, a nut extending below and above the cover and supported thereby, a threaded stem or shaft extending through and engaging said nut, a follower plate carried by said shaft, a flask frame threaded on said nut and held against turning about its axis to the cover and having spaced upright bars, one with an inwardly directed lip extending from one of its vertical edges, and flasks for removable arrangement in said frame below said follower plate,

the flasks being concaved at one side for opposition to one upright bar of the frame and convex at the opposite side for opposition to and cooperation with the lip on the bar of the frame.

3. In a denture press, and in combination, a boiler open at its upper end, an apertured cover for the boiler, means for detachably securing the cover on the boiler, a nut extending below and above the cover and supported thereby, a threaded stem or shaft 70 75 extending through and engaging said nut, a follower plate carried by said shaft, a flask frame threaded on said nut and held against turning about its axis to the cover and having opposite recesses and also having spaced upright bars, one with an inwardly directed lip extending from one of its vertical edges, and flasks for removable arrangement in said frame below said follower plate, the flasks being concaved at one side for opposition to one upright bar of the frame and convex at the opposite side for opposition to and cooperation with the lip on one bar of the frame, the said holding of the flask frame 80 85 against turning about its axis relatively to the cover being effected by pendent projections on the cover co-acting with said opposite recesses in the flask frame.

4. In a denture press, and in combination, 90 95 a flask frame having spaced upright bars, one with an inwardly directed lip extending from one of its vertical edges and a flask for removable arrangement in said frame, the flask concaved at one side for opposition to 100 and reception of one upright bar of the frame and convex at its opposite side for opposition to and cooperation with the lip on said bar of the frame, and the said flask made up of superimposed sections with vent forming 105 notches in their meeting apertures and the said notches so relatively arranged that two of the same will rest at opposite sides of the said lip on the frame bar when the flask is positioned in the frame.

In testimony whereof I affix my signature.

BIRGER UNDERDAHL.
